HAIRPIN

Edward La Pour, Milwaukee, Wis.

Application August 6, 1936, Serial No. 94,610

1 Claim. (Cl. 132—52)

This invention relates to improvements in hairpins and has for its object to provide a hairpin which is self-locking in the hair and cannot work itself loose therefrom.

Another object of the invention is to provide a hairpin having a series of three or more arms coacting with one another to form numerous clamps for engaging whisps of hair therebetween.

Another object of the invention is to provide a hairpin formed of a plurality of three or more coacting cramped arms having the crimps thereof arranged in a novel manner for forming a multiplicity of hair whisp engaging clamps, whereby the working loose of the pin from the hair is prevented.

With these and other objects in view, the invention consists in the novel construction, arrangement, and formation of parts, as will be hereinafter more specifically described, claimed, and illustrated in the accompanying drawing, in which drawing:

Figure 1 is a plan view of one form of my improved hairpin.

Figure 2 is a similar view illustrating a slightly modified form of my improved hairpin.

Referring to the drawing in detail, wherein similar reference characters designate corresponding parts throughout the several views, the numeral 15 indicates one form of my improved hairpin, which comprises a pair of outer legs 16 and 17, and an inner pair of legs 18 and 19. All of the legs 16, 17, 18, and 19 extend in the same direction, and are substantially parallel with one another throughout their entire lengths. The outer ends of the legs 16 and 17 are connected together by substantially U-shaped bight portions 20, and the inner ends of the legs 18 and 19 can be welded to the bight portion in any preferred manner.

Intermediate their ends the legs are each provided with novelly arranged crimps, which function to form a plurality of resilient hair-engaging clamps, whereby the displacement of the pin from the hair is prevented.

In Figure 1, the outer legs 16 and 17 are provided with crimps 23 and 24, which extend in the same direction, but which are out of transverse alinement. The inner legs 18 and 19 are pro-

vided with crimps 25, which extend in the same general direction, and which are in substantial transverse alinement, but out of transverse alinement with the crimps 23 and 24. The adjacent legs of the inner and outer legs have their crimps 5 extending toward one another to form the desired hair-engaging clamps, and the crimps are in contact for a considerable distance so as to prevent displacement of the hair.

In Figure 2, I have illustrated a hairpin formed 10 from three legs, embodying the principles of my invention. Thus, this pin includes a pair of outer legs 40 and 41, and a single intermediate leg 42. The legs 40 and 41 are connected by means of a bowed portion 43, and the intermediate leg can 15 be welded or otherwise secured thereto. The legs 40 and 41 intermediate their ends are provided with a series of crimps 44, which are arranged in staggered relation, that is, the crimps are out of transverse alinement. The center leg 42 is provided with a series of crimps 45, and this leg is of a sinuous form, and the opposite bowed portions thereof engage the inwardly directed portions of the crimps of the outer legs to form a series of staggered arranged pairs of clamps. It is to be 25 noted that the crimps of the inner leg engage the crimps of the outer legs for a considerable distance, so as to provide additional lengths of jaw faces for preventing the displacement of hair.

I lay particular stress on the novel manner in which the pin is formed, whereby I may be able to obtain a series of hair-engaging clamps, which preclude the working loose of the pin. Thus, the hair is always held in a neat and attractive condition.

Changes in details may be made without departing from the spirit or the scope of my invention, but what I claim as new is:

A hairpin comprising, a plurality of longitudinally extending legs all connected at one end, at least one of said legs lying between the other legs, all of said legs having a series of crimps, certain of said crimps having parallel portions arranged in abutting facial contact to provide a 45 series of clamps and a series of hair-receiving pockets.

EDWARD LA POUR.
